United States Patent Office.

H. W. HOLDEN, T. J. MOOERS, D. H. STRATTON, AND G. REYNOLDS, OF BLOSSBURG, PENNSYLVANIA.

Letters Patent No. 66,341, dated July 2, 1867.

IMPROVED ROOF AND CLAPBOARDING BRACKET.

The Schedule referred to in these Letters Patent and making part of the same.

TO ALL WHOM IT MAY CONCERN:

Be it known that we, H. W. HOLDEN, T. J. MOOERS, D. H. STRATTON, and GILBERT REYNOLDS, of Blossburg, Tioga county, Pennsylvania, have invented a new and improved Roofing and Clapboarding Bracket; and we do hereby declare that the following is a full, clear, and exact description thereof, which will enable others skilled in the art to make and use the same, reference being had to the accompanying drawings forming part of this specification, in which—

Figure 1 represents a side view partly in section of our improved bracket, showing the same applied to roofing purposes.

Figure 2 is a side view partly in section of the same, showing it applied to the side of a house for supporting a platform.

Figure 3 is a front view of the bracket.

Similar letters of reference indicate corresponding parts.

This invention relates to a new bracket which can be easily applied to roofs of houses for shingling purposes, or to the sides of houses for supporting platforms for the builders to stand upon, and for many other, and which is so arranged that it will firmly hold itself in position without injuring the boards, posts, or shingles to which it is clamped.

The invention consists in so constructing the main bracket that it will not only hold itself in position, but also so that a truss for supporting the platform in clapboarding, or one for holding the board for shingling, can be easily attached to and held in the bracket.

A represents the bracket, which is made in shape of a wedge-shaped metal plate, to the thick lower end of which a projecting rib, *a*, is cast or otherwise secured, as is clearly shown in figs. 1 and 2. The upper thin end is slotted or forked, as shown in fig. 3. When to be applied to shingles, the thin end is inserted under the uppermost row of shingles laid, while the rib *a* will rest upon the next or one of the next lower shingles, and being provided with pointed steel pins *b*, it will be secured to these shingles as soon as these points are inserted. The bracket is thus firmly held in the manner indicated by fig. 1. When to be used to support horizontal platforms, the thin upper end of the bracket is placed under a clapboard, or a nail is driven in such a manner into the board or post on which the bracket is to be attached, that its head will fit over the edges of the slot, and will therefore prevent the upper end of the bracket from swinging back. The lower end is securely held in position by means of the steel pins *b*, as shown. The lower part of the bracket is perforated by an oblong hole, *c*, above which a downward pointing hook, *d*, is firmly secured to the front of the bracket. *e* is a plate projecting at right angles, or nearly so, from the front of the plate *A*, being strengthened by means of triangular or other braces *f*, which connect its under side with the lower part of the bracket. This plate *e* is arranged in line with the lower end of the hole *c*, and the latter is continued a short distance in the plate *e*. *g g* are two checks arranged on either side of the hole *c*, on the front of the bracket *A*, between the plate *e* and hook *d*, as shown. *B* is a metal or other bar which is provided with a hook, *h*, at one end, and one end of which is passed through a hole, *c*, so that the hook *h* will fit under the hook *d*, as shown in fig. 2. The inner end of the bar or truss *B* is thus held by the hook *d* and plate *e*, while its outer end is supported by a brace, *i*, which is cast to its under side, and of which the inner end rests against the lower part of the bracket *A*, as is clearly shown in fig. 2. It will be seen that the truss *B* is thus set on edge. Lateral motion of the bar *B* is prevented by the checks *g*, and by a stop pin or pins, *j*, which are formed on the under side of the bar *B*, and which fit into holes or slots provided in the plate *e*. The truss *B* is thus firmly secured to the side of the building, and will be capable of supporting a very heavy weight. Its outer end may be provided with an upward projection, *k*, to prevent a board from falling over the end. To the upper edge of the truss are secured pointed steel pins *l* which are pressed into the board that may be placed upon the truss, to prevent the same from slipping. This combined bracket and truss may also be used for other purposes, for suspending weights, &c. *C* is a bar of similar construction as the bar *B*, but is not provided with a brace, *i*. The hook *h* or pins *j* and projection *k* are formed on it as on the brace. It is secured to the bracket when the same is used for roofing, and is held by the hook *d* and plate *e*, as shown, while its outer end is supported by a brace, *D*, which is an independent

bar and is secured in the shingles, as shown in fig. 1. The upper end of the brace D is forked and fits around the bar C between pins *n n* which are secured to the latter. The lower end of the brace D is provided with steel pins *o o*, by which it is held in the shingles, as is clearly shown in fig. 1. The bar C is long enough to allow the application of a board for a rest for the shingles, said board being also able to sustain a number of loose shingles on the roof within easy reach of the workmen.

Having thus described our invention, what we claim as new, and desire to secure by Letters Patent, is—

1. A combined roofing bracket, A, support C, and brace D, when made and operating substantially as herein shown and described.
2. The bracket A, when combined with a truss, B, both made and operating substantially as herein shown and described.
3. The bracket A, with a hook, *d*, and platform *e*, substantially as and for the purposes herein shown and described.
4. The truss B, with a brace, *i*, hook *h*, and lug *j*, and pins *l*, substantially as and for the purpose herein shown and described.
5. The support C, with a hook *h*, pin *j*, and pins *n n*, substantially as and for the purpose herein shown and described.
